(57) **CLAIM**

The ornamental design for a perineal post pad for hip arthroscopy, as shown and described.

DESCRIPTION

FIG. 1 is a perspective view of the perineal post pad for hip arthroscopy;

FIG. 2 is a top view of the perineal post pad for hip arthroscopy;

FIG. 3 is a side view of the perineal post pad for hip arthroscopy;

FIG. 4 is a front view of the perineal post pad for hip arthroscopy;

FIG. 5 is a rear view of the perineal post pad for hip arthroscopy; and,

FIG. 6 is a perspective view of the perineal post pad for hip arthroscopy inserted between the legs of a patient about to have an arthroscopic procedure.

The broken lines in FIG. 6 representing the patient and operating table, show the design as being used, and form no part of the claimed design.
